UNITED STATES PATENT OFFICE.

JOSEPH A. LONZO, OF FITCHBURG, MASSACHUSETTS.

MACHINE FOR CLEANING ROVING BOBBINS.

1,426,303.

Specification of Letters Patent. Patented Aug. 15, 1922.

Application filed February 17, 1921. Serial No. 445,610.

To all whom it may concern:

Be it known that I, JOSEPH A. LONZO, a citizen of the United States, residing at Fitchburg, in the county of Worcester and State of Massachusetts, have invented a new and useful Machine for Cleaning Roving Bobbins, of which the following is a specification.

Machines have been devised for cleaning bobbins used in looms and such machines have reached a high degree of success but on account of the large size and the cylindrical character of roving bobbins it has not been practical to convert the old devices into machines for removing the waste from such bobbins merely by increasing their size or by making ordinary changes in the design which would occur to the machine designer.

The object of this invention is to provide a machine which will effectively clean the waste from such a bobbin that will be capable of getting the bobbins in position, stripping them, and ejecting them without constant attention; also to provide for comparatively rapid operation and uniform and effective action. The invention involves various features and combinations of parts for securing these results.

Reference is to be had to the accompanying drawings in which

Fig. 1 is a side elevation of a machine constructed in accordance with this invention;

Fig. 2 is an end elevation thereof;

Fig. 3 is a sectional view on the line 3—3 of Fig. 2 on an enlarged scale showing the bobbin feeding hopper and one pair of waste stripping jaws;

Fig. 4 is a sectional view on the line 4—4 of Fig. 3 showing part of the stripping mechanism in plan;

Fig. 5 is a side elevation of the yielding stop for the bobbin at the discharge end of the machine;

Fig. 6 is a side elevation of the series of stripping jaw elements and the immediate means for operating them;

Fig. 7 is an elevation of one of the stripping jaws; and

Fig. 8 is a sectional view on the line 8—8 of Fig. 3, and showing the bobbin feeding hopper alone.

I have shown the invention in a form in which a frame 12, or rather the top of it, is provided with a stationary hopper comprising two parallel sides 2 held together by uprights 3 at the sides and back and having

open sides at what are called the forward or discharge end, but this end is closed by one of the uprights 3. This open space is to permit of the insertion of the heads of roving bobbins B. The sides 2 are near enough together on the back of the hopper to prevent the insertion of the bobbin with its head in the opposite position. The top of the hopper flares out to facilitate the reception of the bobbins. At the bottom the hopper is provided with a bottom plate 4 extending almost but not quite across and with a convex projection 5 just above it at one side. The side wall on the right is discontinued a short distance above the member 5 to permit the bobbins to roll out over the side over the rounded discharge edge of the bottom 4. The end members 3 are continued on an inclination at 6 to prevent the bobbins getting out of place longitudinally.

In the form shown the power is received on a tight and loose pulley 10 mounted on a shaft 11 carried in bearings on a frame 12. This shaft by a pair of gears 13 drives a main shaft 14 extending the length of the machine. On this shaft 14 there are two cams 15 of the same shape, size and relative location. On each of these rests a pivoted arm 16 which is held down on the cam by a spring 17 and is raised and lowered by the cam as the main shaft rotates.

Each arm 16 carries a bracket 18 to which is pivoted a twisted link 19 extending upwardly therefrom and adjustably fixed by a bolt 20 and nut in a slot 21 in an arm 22 which is mounted on another arm 23. The bolt 20 can be adjusted at will along the slot 21 to adjust the stroke. The arms 22 and 23 are shown at right angles to each other and constitute a bell crank pivoted on a stand 24. Pivoted connected with the arm 23 is a horizontal link 25 from which extends down an arm 26 and a brace 27, the three elements 25, 26, and 27 on the left hand side of the machine constitute a rigid frame which is capable of moving horizontally. This motion is assured by another link 28 pivoted to the other end of the link 25 and pivotally supported on a bracket 29 fixed in position at the top of the frame. The bottom of the links 23 and 28 are pivoted at fixed points and connected by the longitudinal link 25 which is of the same length as the distance between the pivots. Consequently, this insures a parallel motion.

I have shown two of these structures, one

on each side of the machine. The one on the right is simpler as it does not contain all the elements mentioned.

Connected with the end of the arm 23 is 5 a cross piece 32 to which four springs 30 are connected. Each spring at its opposite end is connected with the top of a lever 31 pivoted on the same pivot preferably as the link 28. Its lower end is the active part 10 which controls other elements as will appear.

Although I have described only one of these structures it is obvious with slight changes the one on the right is substantially the same as the one on the left. It will be 15 obvious that the rotation of the two cams 15 results in the motion of the two frames of which the links 25 constitute the main portion with a parallel motion. It will be understood also that as it moves the several 20 levers 31 are oscillated also.

On the main shaft 14 there is a third cam 35 which bears on a metal plate 36 on the edge of a lever 37. This is pivoted on a stud 38 at the bottom of the machine. Piv- 25 otally connected with this lever are two links 39 at the top of the machine which are pivotally connected with a pusher rod 40 located horizontally in a guide 41 on a bracket 42^a secured to the top of the ma- 30 chine frame. The lever 37 is held back against the cam 35 by a spring 42. The rotation of the shaft 14 causes the lever 37 and consequently the pusher rod 40 to be forced forward quickly and withdrawn even 35 more quickly by the spring.

On the top of the frame is a bracket 43 on which is pivotally mounted a lever 44 having a depending end 45 that is rounded at a point back of the bracket 43. Its ex- 40 treme end is drawn down on top of the frame under normal conditions by a spring 46. On the top of the lever 37 there is a roll 47 which engages the rounded end of the lever 44 on the backward motion of the 45 lever 37 and swings it upwardly about its pivot on the bracket 43. This lever is pro- vided with an extension 48 and with two 50 wires 49 and 50 rigidly fixed to the sup- porting and operating elements 44 and 48 respectively. They are offset from these ele- 55 ments toward the hopper and normally ex- tend down near the open side of the hop- per. When the lever 37 moves way back they are lowered to a position in which they 60 engage the lowest bobbin in the hopper as it tends to emerge therefrom and hold it in the bottom of the hopper. Then when the lever 37 moves beyond a certain point to- 65 ward the front a spring 46 draws them up and this bottom bobbin is released and drops down. At this instant a pair of wires 52 located on the bottoms of the two side frames 26 are projected inwardly into the position shown there.

65 The feed of the bobbin out of the hopper

is also controlled in part by a pair of wires 53 carried by the right hand frame 25 and movable forward and back with the same. There is a stop 54 for preventing bobbins from going over too far.

70 The bobbins are guided down into proper position by two pairs of wires 56 fixedly mounted on the frame 12 and projecting up at the front and rear of the hopper.

When the bobbin gets down into the position shown in Fig. 3 and it is time for the plunger 40 to move forward and force the bobbin through, the frames 25 work to swing back the two sets of levers 31 at the top. This forces them inwardly at the bottom about their pivots. As they project through slots 57 they force forward a corresponding number of jaws 58. These slots 57 are formed by spacing apart brackets or projections 59 on the jaws. These jaws are 80 mounted to slide in two opposite boxes having a bottom 60 and a top 61. On their forward ends they have the steel jaws proper 62 secured to them. These jaws have curved operating surfaces 63 and they are 85 located at a slight angle to a plane exactly transverse to the jaws 58. The consequence is that they project in against the surface of the bobbin and strip the waste therefrom when the bobbin is pushed forward between 95 them.

As the bobbin is forced forward it en- 90 gages a stop 65 which is pivoted on an axis 66 and provided with an arm 67. This arm is connected with a stationary part of the 100 frame by a spring 68 that normally draws the stop up into the normal position shown in dotted lines in Fig. 5 but is capable of yielding into the position shown in full lines in Fig. 5 for letting the bobbin 105 through. This stop merely holds a bobbin through. This stop merely holds a bobbin when it is let down from the hopper and until it is positively pushed through by the plunger 40. A fixed guide 69 is located just 110 behind it for supporting the bobbin as it moves.

In the operation of the device the hopper is supplied with roving bobbins either by hand or automatically. These bobbins are fed down one at a time all in the same posi- 115 tion in the following manner.

First, the wires 53 which engage the bot- 120 tom bobbin and normally hold it in the po- sition A in Fig. 3 are withdrawn as the two frames 25 draw back. The two wires 49 and 50 prevent the bobbin A from moving entirely out of the hopper although it starts out. These wires are necessary be- 125 cause the wires 53 cannot control the move- ment of the bobbin throughout the entire motion of the frame 25. Now the frames 25 move forward and the wires 53 pass in over the bobbin in question while the wires 52 pass into the position shown in Fig. 3 so as to receive the first bobbin as the wires 130

49 and 50 move down. Now the frames 25 again slide back and the springs 30 force the several levers 31 from the position shown in Fig. 3 to that shown in Fig. 1. 5 This forces all the jaws 62 inwardly and they engage the sides of the bobbin at several points. This action is limited by the stops 70 adjustable for different sized bobbins. Now the cam 35 moves from the position shown in Fig. 2 forward and downward and positively moves the pusher rod 40 inwardly as indicated in Fig. 4 thus causing the bobbin to move forward between the jaws. As these jaws are held inwardly 10 against the bobbin by the pressure of the springs 30 they exert a yielding pressure on its sides while it moves by them and take up the waste leaving it on the plunger as indicated in Fig. 4. At the end of its stroke 15 the plunger forces the bobbin through the last pair of jaws and allows it to drop out of the machine over the yielding stop 65, thus positively ejecting it in fully cleaned condition. It moves back and drops the 20 waste in front of the bearing 41 through which it is withdrawn.

As the jaws are all independently forced toward the bobbin by individual springs, an accumulation of too much roving to be 25 stripped will merely cause the first jaw to pass over it taking only part of it and the other jaws will have a chance to receive the balance. There is little danger of breakage from this cause. 30 Although I have illustrated and described only a single form of the invention and shown it as applied only to a single type of bobbin, I am aware of the fact that changes 35 can be made in the details of construction 40 without departing from the scope of the invention as expressed in the claims. Therefore, I do not wish to be limited to all of the details of construction herein shown and described or to the particular shape of bobbin 45 illustrated but what I do claim is:

1. In a machine for cleaning bobbins, the combination with a plurality of pairs of jaws arranged in a series, one pair adapted to engage a bobbin near one end, another 50 pair near the other end and the others at several points along it and to hold it against side motion at both ends, and yielding means for forcing them toward each other to grip the bobbin, of a horizontal pusher rod, and 55 means for forcing said rod horizontally against the end of a bobbin held by said jaws to push it through them and eject it therefrom.

2. In a machine for cleaning roving bobbins, the combination with a plurality of pairs of slidingly mounted jaws and yielding means for forcing them toward each other to grip yieldingly the opposite sides of the bobbin at intervals along it, said jaws 60 being located all at the same elevation, of a

horizontal pusher rod, and positive means for forcing said rod horizontally against the end of a bobbin held by said jaws to push it through them and eject it therefrom.

3. In a machine for cleaning bobbins, the combination with a plurality of pairs of jaws, means for guiding said jaws to slide in a plurality of planes, and yielding means for forcing them toward each other to grip the bobbin, of a horizontal pusher rod, 75 means for forcing said rod horizontally against the end of a bobbin held by said jaws to push it through them and eject it therefrom, and yielding means for drawing the pusher rod back. 80

4. In a roving bobbin cleaning machine, the combination of a plurality of pairs of sliding jaws oppositely located, a lever for operating each jaw, loosely connected therewith and mounted in the plane of its jaw 85 and above it, a separate spring for moving each lever to force its jaw in, and positive means having an adjustable stroke for moving said levers out simultaneously.

5. In a bobbin cleaning machine, the combination with a plurality of jaws, a lever for operating each jaw, a spring for moving each lever to force its jaw in, means for moving said springs out simultaneously, and yielding means for moving the springs 95 inward bodily.

6. In a bobbin cleaning machine, the combination with a plurality of opposite pairs of spring pressed roving removing jaws, means for closing them, and means for forcing a bobbin to move through the several pairs to strip the roving therefrom, of a hopper above the jaws for receiving the bobbins, said hopper having sides arranged at one end near together and terminating short 100 of the other end for preventing a roving bobbin being put into it wrong end to. 105

7. In a bobbin cleaning machine, the combination with two opposite sets of spring pressed jaws arranged in pairs, means for closing each pair, means for forcing a bobbin to move through the several pairs of jaws, of a hopper above the jaws for receiving the bobbins, said hopper being open at one side, and means operated by the bobbin 110 forcing means for periodically preventing the bobbins from dropping out through the open side. 115

8. In a bobbin cleaning machine, the combination with two opposite sets of spring 120 pressed jaws, each set comprising a plurality of parallel jaws, means for closing the jaws, means for forcing a bobbin to move through the several pairs of jaws, of a hopper above the jaws for receiving the bobbins, said hopper being open at one side, and two alternately operating means for holding the bobbins back in the hopper, one operated by the bobbin forcing means and the other by the jaw closing means. 125 130

9. In a bobbin cleaning machine, the combination with two opposite sets of spring pressed jaws, means for closing them, means for forcing a bobbin to move between the two sets, of a hopper above the jaws, but at one side thereof, for receiving the bobbins, said hopper being open at one side, means operated by the bobbin forcing means for periodically preventing the bobbins from dropping out through the open side, and means movable with the jaws for supporting a bobbin between the two sets of jaws.
10. In a machine for cleaning bobbins, the combination with a plurality of pairs of
- jaws and yielding means for forcing them toward each other to grip the bobbin, of a horizontal pusher rod, means for forcing said rod horizontally against the end of a bobbin held by said jaws to push it through them and eject it therefrom, and a yielding forwardly movable stop for engaging the forward end of a bobbin between the jaws and holding it until the pusher acts, said stop being capable of yielding to the positive action of the pusher rod to allow the bobbins to be pushed out.

In testimony whereof I have hereunto affixed my signature.

JOSEPH A. LONZO.
